UNITED STATES PATENT OFFICE.

JAMES P. COLE, OF GLENVIEW, ILLINOIS.

HEAT GENERATION.

1,114,113.

Specification of Letters Patent. Patented Oct. 20, 1914.

Application filed April 12, 1911. Serial No. 620,708.

To all whom it may concern:

Be it known that I, JAMES P. COLE, a resident of Glenview, in the county of Cook and State of Illinois, have invented certain new and useful Improvements in Heat Generation, of which the following is a full, clear and exact description.

The invention relates to heat generation, for example, such as may be utilized in steam-boilers.

Heretofore attempt has been made to burn lignite for generating steam in locomotive-boilers, but it has been found in practice, that elimination of the moisture in the lignite, either in the combustion-chamber, or even before, would cause the lignite to disintegrate or break up into small pieces or flakes, which, owing to its comparatively light specific gravity, would be carried by the draft out of the combustion-chamber and through the chimney or stack, from which it would issue before combustion had been completed, and therefore these burning pieces or flakes would cause damage by fire. For this reason, lignite has not been regarded as safe fuel in locomotive-boilers, in which a forced draft is usually used. Furthermore a considerable percentage of the disintegrated lignite would fall through the grates of the fire box before it was consumed and for that reason a considerable loss in economy resulted.

The present invention designs primarily, to provide an improved furnace for heat generation mainly from pulverized lignite or similar material, which will be economical in result, because all portions of the combustible constituents of the lignite will be consumed before the products of combustion reach the stack, thereby avoiding all danger of fire resulting from large burning sparks being carried through the boiler and issuing from the stack.

The invention designs to provide a furnace for the use of pulverized fuel, such as lignite, with means for conducting the pulverized fuel to the combustion chamber, with means for delivering steam and gas to said combustion chamber, the chamber being so constructed as to allow the mixture of the pulverized fuel with the ignited gas, and means for conducting this mixture of gas, steam and fuel from the combustion chamber.

The invention further designs to provide

a new and improved furnace for the use of pulverized lignite or similar material.

In the drawings which exemplify an apparatus for carrying out the improved method; Figure 1 is a central vertical section through a locomotive boiler equipped for the combustion of pulverized lignite or other fuel. Fig. 2 is a section taken on line 2-2 of Fig. 1. Fig. 3 is a section taken on line 3-3 of Fig. 1. Fig. 4 is a horizontal section taken on line 4-4 of Fig. 1. Fig. 5 is a rear elevation of the boiler. Fig. 6 is a section through the carbureter. Fig. 7 is a detail showing the injectors for the pulverized fuel and air. Fig. 8 is a detail showing the gas-inlet and steam-injectors. Fig. 9 is a detail of the pulverized fuel-supply.

The improved furnace comprises a boiler 15 equipped as usual with a steam dome 16, a smoke arch 17, a stack 18, front and rear flue sheets 19 and 20 and a crown-sheet 21. A combustion-chamber is provided at the rear of the boiler, and is divided horizontally, by a series of fire-brick arches 22 and vertically, by walls 23 which sub-divide the spaces between the arches into longitudinal passages or flues 23^a. Arches 22 are formed with holes 24 which permit the gases to pass upwardly through the arches, and a chamber 25 is formed between the upper arch 22 and the crown-sheet 21. The front of the combustion-chamber is formed by a rearwardly arched wall 26, which is built against an inwardly extending channel strip or ring 27. A chamber 28 is formed between the rear flue-sheet 20 and wall 26. Ports 29 conduct the gases from the combustion chamber of the box fire to the chamber 28.

Previously pulverized lignite or similar fuel is taken from the supply hopper 30, and passes in regulated quantity, under control of a valve 31, to a pipe 32. A jet 33 connected to a source of compressed air, forces the pulverized fuel through pipe 32 and through nozzles 33', and supplemental air jets 34 aid in drawing the pulverized fuel through pipe 32 and in forcing the fuel into ducts 35 which extend longitudinally through the two upper series of walls 23. Laterally extending openings 36, in said walls direct the pulverized fuel and air into the chambers 23^a. The pulverized fuel is delivered to the upper series of ducts, so that the gas supplied to the combustion-chamber at a lower level will rise and mingle with the

air and pulverized fuel in transit through the upper chambers 23^a and will aid in keeping the pulverized fuel in suspension and circulation. Valves 38 and 39 control the 5 volume of air supplied to the combustion-chamber and serve to regulate the supply of air, for thorough combustion.

A carbureter 40, adapted to contain a supply of crude oil, is secured to the wall 41 of the fire-box so that the oil therein will be kept at a suitable temperature for vaporization by heat radiating from the back of the fire-box. Insulation 43 extends around the exposed portion of the carbureter. Oil, 10 in regulated quantity, is supplied to the carbureter by a suitable pump (not shown). A pipe 45 extends through the oil in the carbureter and a nozzle 46, connected to the steam-supply directs a jet of steam through 15 said pipe to draw the vapor or gas formed in the carbureter through pipe 45. A perforated plate or wall 47 extends across the chamber in the carbureter in the top thereof and the vapor is drawn through the perforations in said plate.

A pipe 48 is connected to the lower end of pipe 45 and conducts the gas and steam to a series of injectors 49 which direct the steam and gas into longitudinal ducts 50 formed respectively in the walls 23 between the three lower arches in the combustion-chamber, and openings 51 extend laterally from said ducts to chambers or flues 52, from which the gases pass through transverse ducts 53 to the chambers or flues 23^a. Valves 54 serve to regulate the volume of gas and steam supplied to the combustion-chamber. Thus, gas and steam will be injected into the lower flues 52 of the 35 compartments of combustion-chamber, and pulverized lignite and air, with the lignite in suspension, will be forced to circulate through the upper chambers 23^a of the fire box. Burning gas will pass upwardly from 40 chambers or flues 52 through the openings in walls 22, and into the chamber 23^a in which the pulverized fuel is in suspension and through which it circulates. The gas will keep the fire-box and its walls therein 45 hot, and will ignite and mingle with the pulverized fuel, and the resultant mixture, will pass through openings 24 in the uppermost arch wall 22 and also through opening 29 in wall 26, to the chamber 28 and thence 50 in transit through the combustion-chamber. The ignited gases and fuel will come in contact with the crown-sheet and walls of the fire-box, so that the water in this section of the boiler will be heated thereby. The 55 ignited gases and fuel, after passing into chamber 28 will pass through the flues of the boiler to the smoke-arch 17 and thence to the stack. In transit through the boiler-flues the heat-units of the fuel will be transferred to the water surrounding the flues

and the fuel will be fully consumed by the time the products of combustion reach the stack.

A desideratum in steam-generation, is to avoid, so far as possible, the use of excessive 70 quantity of oil or oil gas because of their destructive effect on the flues, flue sheets and walls of the fire-box. A minimum amount of gas is supplied to the fire-box merely sufficient to insure combustion of the 75 lignite, and a maximum of the pulverized lignite or fuel; say from 5 to 20 per cent. of gas, and 80 to 95 per cent. of pulverized fuel, with sufficient oxygen carrying this pulverized fuel in suspension, and this 80 supply will result in thorough combustion of the fuel and there will be substantially no unconsumed powder issuing from the stack.

Beneath the lower arch-wall 22, is formed 85 an ash-pit which is adapted to receive the ashes which do not pass through the flues to the stack. The bottom of the ash-pit is formed by pivoted members 60, of fire tile, which, when closed, will prevent the fuel 90 from falling through the ash-pit and will also prevent excessive admission of cold air to the fire box.

The furnace thus described, exemplifies one for heat-generation by the use of pulverized or reduced lignite or other similar fuel delivered in suspension, into the combustion-chamber with sufficient air to supply the oxygen necessary for combustion; with a comparatively small volume of gas delivered into the combustion chamber by and with steam; the gas sufficing to heat the walls of the fire-box, and commingling with the powdered fuel in suspension in the combustion-chamber to form a highly combustible mixture causing the pulverized fuel to be thoroughly consumed so the heat units will be transferred to the water in the boiler and so that all the heat units will be substantially and completely extracted before 100 the products of combustion issue from the stack. In this manner the invention provides a furnace for utilizing lignite in heat-generation economically and without danger of fire due to pieces of ignited fuel passing 105 out of the stack. This furnace effects advantageous generation of heat from lignite and makes its consumption a practical and commercial success, by reason of its being pulverized or reduced to small particles, and by use of a comparatively small quantity of gas or combustion vapor derived from gas or oil. A decided advantage of the furnace is the generation of heat controlled at will 110 by regulation of the supply of pulverized fuel and air, as well as gas and steam. The generation may be regulated and be continuously maintained to uniformly heat a body of water in the boiler so that the heat-generation and supply of steam will be constant 115 120 125 130

and uniform. Furthermore the improved furnace provides for thoroughly co-mingling the gases and pulverized fuel by causing them to pass in an irregular course and 5 retarding them so that the pulverized fuel will be incandescent when it passes into the flues.

The invention is not to be understood as restricted to the specific feature of this furnace, as set forth, but may be varied within 10 the scope of the appended claims without departing from the spirit or the scope of the invention.

Having thus described the invention what 15 I claim as new and desire to secure by Letters Patent is:

1. In a furnace, the combination of a combustion chamber having vertically and laterally extending walls dividing the chamber 20 into a series of combustion flues, means for delivering pulverized fuel in suspension to said flues, and means for supplying gas to said flues.

2. In a furnace, the combination of a combustion chamber having refractory walls extending vertically and laterally to divide the combustion chamber into a series of 25 flues, means for delivering pulverized fuel in suspension to said flues, and means for 30 supplying gas to said flues.

3. In a furnace, the combination of a combustion chamber having refractory walls extending vertically and laterally to divide the combustion chamber into a series of 35 flues, said walls having ducts leading to said flues and extending between them, means for delivering pulverized fuel in suspension to said flues, and means for supplying gas to said flues.

4. In a furnace, the combination of a combustion chamber having vertically and laterally extending walls dividing the chamber 40 into a series of combustion flues, means for delivering pulverized fuel in suspension to some of said flues, other flues for combustible 45 gas, means for supplying gas to said latter flues, and ducts leading from the gas flues to the flues to which the pulverized fuel is delivered.

5. In a furnace, the combination of a combustion chamber having vertically and later-

ally extending walls dividing the chamber into a series of combustion flues, means for delivering pulverized fuel in suspension to said flues, a chamber adjacent one end of 55 said combustion chamber to which the products of combustion pass, and means for supplying gas to said flues.

6. In a furnace, the combination of a combustion chamber having vertically and laterally extending walls dividing the chamber 60 into a series of combustion flues, means for delivering pulverized fuel in suspension to said flues, a chamber in the combustion chamber above the top of said flues to 65 which the products of combustion pass, and means for supplying gas to said flues.

7. In a furnace, the combination of a combustion chamber having vertically and laterally extending walls dividing the chamber 70 into a series of combustion flues, means for delivering pulverized fuel in suspension to said flues, a chamber in the combustion chamber at the top of the flue and a chamber at the end of the flues to which the products of combustion pass in the chamber above the flues, and means for supplying combustible gas to said flues.

8. In a furnace, the combination of a combustion chamber having refractory walls extending vertically and laterally to divide the combustion chamber into a series of flues, means for delivering pulverized fuel in suspension to some of said flues, means for delivering steam and gas to other of the flues, 85 and ducts between the gas flues and the flues to which the pulverized fuel is delivered.

9. In a furnace, the combination of a combustion chamber having vertically and laterally extending walls dividing the chamber 90 into a series of flues, means for delivering pulverized fuel in suspension to some of the flues of said chamber, means for supplying gas and steam to other of the flues, ducts 95 between said flues and a chamber to which the burning fuel will pass.
